(Cl. D49—1)

To all whom it may concern:

Be it known that I, Emma G. Hager, a citizen of the United States, residing at Max Meadows, in the county of Wythe and State of Virginia, have invented a new, original, and ornamental Design for Laundry Tongs, of which the following is a specification, reference being had to the accompanying drawing, forming part thereof.

In the drawing:

Figure 1 is a front elevational view of a laundry tongs showing my new design;

Figure 2 is a rear elevational view thereof;
Figure 3 is a side elevational view thereof;
and

Figure 4 is a top plan view thereof.

I claim:

The ornamental design for a laundry tongs, as shown.

EMMA G. HAGER.
